UNITED STATES PATENT OFFICE.

HENRY J. BLAKESLEE, OF WEST HARTFORD, CONNECTICUT.

COUPLING TRANSFORMER.

Application filed May 23, 1924. Serial No. 715,293.

To all whom it may concern:

Be it known that I, HENRY J. BLAKESLEE, a citizen of the United States, residing at West Hartford, in the county of Hartford and State of Connecticut, have invented a new and useful Improvement in Coupling Transformers, of which the following is a specification.

This invention relates to coupling transformers designed for radio work, more particularly amplifying transformers of the shell type adapted for amateur use.

The object of the invention is the production of very simple independent elements which can be manufactured and sold at a very low price and can be put together by a user in any primary and secondary ratio desired, the elements being so shaped that it is impossible to assemble them in any but the right way, that is, with the windings in the same direction.

In the accompanying drawings Fig. 1 shows a plan of an insulating spool upon which the wire is wound. Fig. 2 shows a plan of the spool with the wire coiled thereon. Fig. 3 shows an edge view of the wound element. Fig. 4 shows a face view of the soft iron core pieces which are thrust through the wound spools. Fig. 5 shows a view of one side of the assembled core and coils. Fig. 6 shows an edge view of the assembled transformer elements. Fig. 7 shows a view of the other side of the transformer elements. Fig. 8 shows a side elevation of the elements as they may be encased in a shell. Fig. 9 shows an edge view with the elements encased in a shell. Fig. 10 shows a top view of the encased elements. Fig. 11 shows a plan of a piece of sheet insulation that may be used to reinforce and protect an element.

In carrying out this invention identical elements, each comprising an insulating spool 1 which is wound with the desired number of turns of fine wire 2, are made up in quantities and sold as desired. The ends of the windings are provided with terminals 3 adapted to be connected together or with primary binding posts 4 or secondary binding posts 5 as the case may be. Thin sheet insulating pieces 6 are desirably bent around the spools for protection and to provide means for the ready joining of the ends of the windings to the terminal wires. The insulating spools have openings 7 for re-

ceiving the laminated iron core pieces 8, and perforations 9 for the bolts 10 by which they are bound together. The bolt holes through the spools are, as illustrated, located off center with relation to the core holes in such positions that the elements cannot be put together wrong, that is, they must be assembled with the windings running in the same direction or the holding bolts cannot be passed through them. This is so whether the terminals project on one side or on the other side. After these elements are fastened together the core pieces are thrust through the openings in the spools. Each core piece has three legs one in the center and one each side, joined together at one end only. One core piece is put through the elements in one direction and the next in the opposite direction so that the closed ends of the core pieces will alternate on the opposite ends of the assembled units. The core pieces may be bolted together by screw bolts 11.

Identical elements suitable for both primary and secondary windings are produced in quantities and they are assembled preferably with the primary winding ends on one side and the secondary winding ends on the other side. The drawings illustrate a two to six ratio transformer, that is, one with two coils connected in series and joined with the primary binding posts and six coils connected in series and joined to the secondary binding posts. It is possible as a result of this invention for a user to purchase the required number of coils and core pieces and assemble them himself in any desired ratio and with the winding ends in convenient position to be easily connected with the proper binding posts. As the windings are identical and as the means for fastening together the elements are arranged it is impossible for the user to assemble the parts incorrectly. The windings must always be in the same direction. Should it be desired to alter the ratio it is only necessary to make such a change in the connection of the terminals of the windings as will produce the required result. The transformer elements proper may be enclosed in any suitable frame as for instance in shell pieces 12. This conception enables independent elements to be manufactured in quantities and sold very cheaply, and the parts to be put together by an unskilled user without danger of assembling them wrongly.

The invention claimed is:—

1. A transformer which comprises a plurality of insulating spools having similar windings and means for registering one spool with the other with the windings in the same direction, means co-operating with said registering means for fastening the spools together flatwise with the windings in the same direction, said fastening means being capable of application only when the spools are assembled flatwise with the windings in the same direction, and core pieces adapted to be thrust through the wound spools.
2. A transformer which comprises a plurality of insulating spools having similar windings, and means for registering one spool with the other when the spools are placed face to face with the windings in the same direction, means for fastening the spools when registered with the windings in the same direction, said fastening means being capable of application only when the spools are assembled face to face with the windings in the same direction, and a laminated core comprising pieces thrust through the wound spools alternately in opposite directions.
3. A transformer element for radio use comprising an insulating spool having a core opening and fastening perforations, and a winding of fine wire upon the spool, said fastening perforation being located obliquely with relation to the axis of the core opening so that a plurality of elements can be fastened together only when the windings are in the same direction.
4. A transformer element for radio use which comprises a spool of insulating material, a winding of fine wire upon said spool and sheet insulation bent about a portion of said wound spool adjacent to the ends of the winding.
5. A transformer for radio work which comprises a plurality of independent coils assembled face to face with the windings of all running in the same direction, and arranged with the terminals of some of said coils extending on one side and the terminals of other of said coils extending on the other side of the assembled elements, means for fastening the coils together face to face, and core pieces shaped to be thrust through the coils from opposite directions.
6. A transformer comprising a plurality of insulating spools provided with similar windings and having means for registering one spool with the other with the windings in the same direction, means for fastening the spools together flatwise as registered with the windings in the same direction, and core pieces thrust through the wound spools.
7. A transformer comprising a plurality of insulating spools provided with similar windings, a laminated core thrust through the wound spools and means arranged obliquely to the plane of the core for fastening the spools together flatwise with the windings in the same direction, said means thus arranged being capable of application only when the spools are assembled with the windings in the same direction.

HENRY J. BLAKESLEE.
